FRANCIS B. DE BROCK, OF KEW GARDENS, NEW YORK

DESIGN FOR A SHOE SHINING CABINET

Application filed February 24, 1932. Serial No. 42,974. Term of patent 7 years.

To all whom it may concern:

Be it known that I, FRANCIS B. DE BROCK, a citizen of the United States of America, residing at Kew Gardens, State of New York, have invented a new, original, and ornamental Design for a Shoe Shining Cabinet, of which the following is a specification, reference being had to the accompanying drawings, forming a part hereof.

Figure 1 is a perspective view of a shoe shining cabinet embodying my design.

Figure 2 is a side elevation of my shoe shining cabinet of Figure 1.

Figure 3 is an end elevation.

Figure 4 is a top plan.

I claim:

The ornamental design for a shoe shining cabinet, substantially as shown.

FRANCIS B. DE BROCK.
